(57) **CLAIM**

The ornamental design for a hook mount, as shown and described.

DESCRIPTION

FIG. 1 is a perspective view of our design;

FIG. 2 is a front view thereof;

FIG. 3 is a left side view thereof;

FIG. 4 is a right side view thereof;

FIG. 5 is a top view thereof; and,

FIG. 6 is a bottom view thereof.

The dashed lines in the figures represent environmental structure that forms no part of the claimed design. All other surface (s) or portion(s) of our hook mount not shown in the figures or otherwise described in the specification, including the back view thereof, form no part of the claimed design.
